US00D678062S

(12) **United States Design Patent**
Vanden Boom et al.

(10) **Patent No.:** **US D678,062 S**
(45) **Date of Patent:** **** Mar. 19, 2013**

(54) **PACKAGE**

- (71) Applicant: **Kimberly-Clark Worldwide, Inc.,**
 Neenah, WI (US)
- (72) Inventors: **Heidi Ellen Vanden Boom**, Appleton, WI (US); **Dayton Joel Henderson**, Appleton, WI (US); **Robert Eric MacDonald**, Kohler, WI (US); **Michael Patrick McCuskey**, Cincinnati, OH (US); **Christine Marie Mau**, Neenah, WI (US)
- (73) Assignee: **Kimberly-Clark Worldwide, Inc.,**
 Neenah, WI (US)

(**) Term: **14 Years**(21) Appl. No.: **29/436,279**(22) Filed: **Nov. 2, 2012**

OTHER PUBLICATIONS

Co-pending U.S. Appl. No. 29/357,012, filed Mar. 5, 2010, by Vanden Boom et al. for "Package Design."

(Continued)

Primary Examiner — Robert M Spear

Assistant Examiner — Rashida C McCoy

(74) *Attorney, Agent, or Firm* — Sarah Ann Dressel

(57) **CLAIM**

We claim the ornamental design for a package, as shown and described.

DESCRIPTION

The FIGURE is a perspective view of a package showing the ornamental design.

The broken lines in the drawing represent unclaimed environmental subject matter.
